OSKAR SEITZ, OF BADEN, SWITZERLAND

ELECTRIC CURRENT RECTIFIER

Application filed August 26, 1930, Serial No. 477,807, and in Germany August 2, 1929.

This invention relates to improvements in electric current rectifiers and particularly to a rectifier construction in which the usual single cathode is divided into a plurality of 5 separate electrically connected portions each acting for a portion of the anodes of the rectifier.

When an electric current rectifier for high current and of the metallic vapor type is provided with a plurality of anodes which are so arranged as to operate in conjunction with a plurality of cathode portions, electrically forming a single cathode, the arc to be maintained between an anode or group of anodes to a certain cathode portion can be kept in the proper path and caused to attach to the desired cathode portion only with great difficulty if at all. Such operation with its substantially constant use of one 15 cathode portion leads to excessive vaporization of the cathode material with all of the known difficulties and disadvantages in rectifier operation attendant thereon.

It is, therefore, among the objects of the 20 present invention to provide an electric current rectifier construction of the metallic vapor type in which the arc is forced to attach to the desired one of several cathode portions.

Another object of the invention is to provide an electric current rectifier construction for high currents in which the anodes are divided into groups and the cathode is divided to provide a cathode portion for each 25 anode group.

Another object of the invention is to provide an electric current rectifier construction in which the arc originating at one group of anodes is forced to flow to a pre-determined 30 portion of a divided cathode.

Objects and advantages, other than those above set forth, will be apparent from the following description when read in connection with the accompanying drawings in 35 which

Figure 1 is a horizontal cross-section, taken on the line A—A of Fig. 2, of a rectifier structure embodying the present invention, and

Fig. 2 is a vertical cross-sectional view of 50 the electric current rectifying structure taken on the line B—B of Fig. 1.

Referring more particularly to the drawings by characters of reference, the reference numeral 3 designates an open topped tank or cylinder which is formed with double walls to provide a path for the circulation of a cooling medium therethrough. The tank 3 is closed by a cover plate 4 having a plurality of groups of anodes 6, 7 and 8 extending 55 therethrough in insulated relation therewith. The anode plate 4 is apertured substantially centrally thereof, which aperture is closed by a cooling dome 9 extending upwardly therefrom and is formed with double walls 60 to provide a portion of the circulating path for the cooling medium flowing through the space between the walls of the tank 3. The anode groups 6, 7 and 8 are preferably each 65 arranged in an arc which is substantially a semi-circle arranged in such a manner that lines tangential to the center of an arc are also tangential to opposite ends of the arcs of the other groups. It will be understood 70 of course, that the anodes may be connected to form a portion of either a three or a nine phase system.

The bottom of the tank 3 is formed in a downwardly extending multi-cone shape to permit the formation, in conjunction with 75 closure plates 11, 12 and 13, of pockets or wells equal in number to the number of anode groups or to the number of phases which wells are arranged to receive material forming the cathode portions 16, 17 and 18. The 80 plates 11, 12 and 13 are, of course, suitably insulated from the tank 3.

An aperture formed substantially centrally in the bottom of the tank 3 is closed in 85 insulated relation therewith by a tube 19 90

closed at the upper end and extending upwardly from the bottom interiorly of the tank 3. The tube 19 is thus in contact interiorly thereof with the atmosphere and exteriorly thereof with the vaporized cathode material within the tank and forms one means for extracting heat from the vapor and for condensing the same. A plurality of metallic walls 21, 22 and 23 extend from and are both thermally and electrically conductively connected with both the tube 19 and the walls of the tank 3. Such walls preferably extend upwardly from the bottom of the tank 3 into the plane of the lower surfaces of the anode groups thereby substantially dividing the tank into a plurality of compartments each containing one anode group and one cathode portion. It will be understood that the tube 19 as well as the walls 21, 22 and 23 may be made double-walled for the purpose of forming a portion of the path for the circulation of a cooling medium therethrough to reduce the temperature prevailing in the center of the tank 3. The walls need not be joined to the tank 3 and the tube 19 in an air-tight manner and may be provided with apertures at suitable points to permit easier evacuation of the tank by a single evacuating device (not shown).

Although but one embodiment of the present invention has been illustrated and described, it will be apparent to those skilled in the art that various changes and modifications may be made therein without departing from the spirit of the invention or from the scope of the appended claims.

The invention claimed is:

1. In an electric current rectifier of the metallic vapor type, a closed tank, a plurality of groups of anodes extending into said tank, a cathode divided into a plurality of portions equal in number to the number of said anode groups and arranged in the bottom of said tank, and metallic walls substantially separating said groups of anodes into separate compartments within said tank.

2. In an electric current rectifier of the metallic vapor type, a closed tank, a plurality of groups of anodes extending into said tank, a cathode divided into a plurality of portions equal in number to the number of anode phases and arranged in the bottom of said tank, and metallic walls conductively connecting the walls of said tank and substantially dividing said tank into a number of compartments equal to the number of anode groups and cathode portions.

3. In an electric current rectifier of the metallic vapor type, a closed tank, a plurality of groups of anodes extending into said tank, a cathode divided into a plurality of portions equal in number to the number of said anode groups and arranged in the bottom of said tank, a tube closed at the upper end thereof and extending upwardly from the bottom

and interiorly of said tank, the interior of said tube being in contact with the atmosphere, and metallic walls conductively connected with and substantially dividing said tank into a number of compartments equal to the number of anode groups and cathode portions.

In testimony whereof I have hereunto subscribed my name this 13th day of August, A. D. 1930.

OSKAR SEITZ.
